UNITED STATES PATENT OFFICE

147,701

DESIGN FOR A SPINNING TOY

Harry Aaron Tomarin, Cincinnati, Ohio

Application March 26, 1946, Serial No. 127,955

Term of patent 14 years

(Cl. D34—15)

To all whom it may concern:

Be it known that I, Harry Aaron Tomarin, a citizen of the United States, residing at Cincinnati, in the county of Hamilton and State of Ohio, have invented a new, original, and ornamental Design for Spinning Toys, of which the following is a specification, reference being had to the accompanying drawings, forming part thereof.

Fig. 1 is a side elevational view of a spinning toy showing my new design;

Fig. 2 is a front elevational view of the spinning toy;

Fig. 3 is a top view of my spinning toy.

I claim:

The ornamental design for a spinning toy, as shown.

HARRY AARON TOMARIN.
